J. M. B. LEWIS,

Inventor

By C. L. Parker
Attorney

UNITED STATES PATENT OFFICE.

JOHN MINOR BOTT'S LEWIS, OF LYNCHBURG, VIRGINIA, ASSIGNOR TO LIVESTOCK INDIVIDUAL DRINKING FOUNTAIN COMPANY, INC., OF LYNCHBURG, VIRGINIA, A CORPORATION OF VIRGINIA.

DRINKING APPARATUS.

1,317,801.

Specification of Letters Patent.

Patented Oct. 7, 1919.

Application filed May 2, 1917. Serial No. 165,874.

To all whom it may concern:

Be it known that I, JOHN M. B. LEWIS, a citizen of the United States, residing at Lynchburg, in the county of Campbell and State of Virginia, have invented certain new and useful Improvements in Drinking Apparatus, of which the following is a specification.

My invention relates to improvements in drinking receptacles or troughs for cattle, horses, and the like.

An important object of the invention is to provide means whereby the water in one receptacle cannot flow back into the common supply pipe and be thereby supplied to other receptacle or receptacles.

A further object of the invention is to provide reliable and simple means to adjust the pressure at which the water is supplied into the drinking receptacle, thus preventing the same being forced or thrown upwardly beyond the receptacle, or into the face of the animal, while drinking.

A further object of the invention is to provide means for causing the incoming water, to flow downwardly in proximity to the exterior of the inlet conduit, whereby it is remote from the forward end of the receptacle, and the mouth of the animal, while drinking.

A further object of the invention is to improve the apparatus in general, by assembling the various parts thereof in a highly convenient and compact manner.

A further object of the invention is to provide improved and simplified means to thoroughly drain the receptacle.

Other objects and advantages of the invention will be apparent during the course of the following description.

In the accompanying drawings forming a part of this specification, and in which like numerals are employed to designate like parts throughout the same,

Figure 1 is a side elevation of apparatus embodying my invention,

Fig. 2 is a central vertical longitudinal sectional view taken on line 2—2 of Fig. 3,

Fig. 2^a is a detailed section through the drain conduit, showing the outlet opening thereof,

Fig. 3 is a plan view of the apparatus, a portion of the cover being broken away.

Fig. 3^a is a bottom plan view of the cap carried by the vertical inlet pipe.

Fig. 4 is a transverse sectional view taken on line 4—4 of Fig. 3.

Fig. 5 is a detail horizontal section through the water supply conduit, taken on line 5—5 of Fig. 2, and,

Fig. 6 is a perspective view of a combined screen and guard.

In the drawings, wherein for the purpose of illustration is shown a preferred embodiment of my invention, the numeral 10 designates a drinking receptacle or bowl, the upper end or top of which is open, as shown. This bowl has its bottom formed in a rear portion 11, which is inclined forwardly, to meet with a rearwardly inclined forward portion 12, which is curved in cross-section, as shown. Formed in the rear portion 10 is a depending rearwardly inclined passage or pocket 13, which is substantially V-shaped in cross-section and increases in depth rearwardly. The forward end of this pocket terminates near or at the union of the forward and rear bottom portions 11 and 12, as shown. The pocket or passage 13, at its rear end, is provided with an outlet opening 14, discharging into a lateral extension 15 of a drain conduit 16, and having free communication therewith, as shown. The drain conduit 16 projects interiorly above the bottom portion 11, within the receptacle 10, forming an overflow conduit 17, the upper end of which determines the maximum water level of the drinking receptacle 10, as shown. It is thus apparent that the overflow water from the conduit 17 and the drain water from the pocket or passage 13, discharge through the conduit 16, which may be connected with a suitable pipe (not shown) discharging at a suitable point.

The numeral 17' designates an apertured guard-plate, arranged diagonally in the corner of the drinking receptacle, above and adjacent the upper end of the conduit 17. The plate 17' has depending legs 18' and 19'. The legs 18' are arranged exteriorly of the conduit 17, in contact with the walls of the same, while the leg 19' extends into the con-

duit. These legs serve to hold the guard-plate 17' in place.

Arranged within the rear portion of the drinking receptacle 10 is a water inlet conduit 18, preferably vertically arranged, and having its upper discharge end, disposed a substantial distance above the upper intake end of the overflow conduit 17, as clearly illustrated in Fig. 4. The function 10 of this construction is to provide means whereby the water in the receptacle 10 cannot flow back into the inlet conduit 18, and thereby pass to the common supply pipe. The inlet conduit 18 has a reduced tubular 15 extension 19, screw-threaded into an opening 20, of a coupling 21, adapted for connection with a water supply pipe (not shown). The tubular extension 19 has a contracted bore 22, adapted to be partly or wholly closed by 20 a bolt or valve 23, having screw-threaded engagement within an opening 24, the free end of this bolt being adapted to enter an opening 25, as shown. The function of this bolt or valve is to provide means for regu- 25 lating the volume of water passing through the bore 22 and discharging into and through the inlet conduit 18, in turn regulating the pressure of the water at the discharge end of the conduit 18. It has been found necessary 30 to provide some means to reduce the pressure of the water discharging from the inlet conduit 18, particularly where the apparatus is used or connected with a water supply system, operating under high pressure, as 35 such high pressure water would be thrown above the receptacle and in many instances into the face of the animal drinking. The tubular inlet conduit is provided near the upper end of the bore 22 with a contracted 40 drain or weep port 26.

The inlet conduit 18 is provided interiorly thereof and near its upper end with lugs 27, adapted to engage with a suitable tool placed therein for turning the conduit 45 18, for screwing or unscrewing the same within and from the opening 20.

Arranged above the discharge end of the inlet conduit 18 is an imperforate preferably circular cap 28, provided upon its lower 50 side with an annular set of spacing spaced lugs 29, adapted to contact with the upper end of the conduit 18, thereby retaining the cap 28, spaced therefrom. The cap 28 is provided with a depending annular flange 55 30, surrounding the upper end of the conduit 18, in concentric spaced relation, and this flange is preferably provided with spaced interior lugs 31, to contact with the exterior of the conduit 18, thus retaining 60 the cap in the concentric relation thereto. The cap 28 is provided centrally thereof with a depressed portion 32, having an opening 33 formed therein, as shown.

The numeral 34 designates a cover for

the drinking receptacle 10, provided at its 65 forward end with an up-turned lip 35, having a lug 36 therebelow, to contact with a plug of rubber 37, held within a socket 38. The cover 34 is provided at its rear end with a knuckle 39, pivotally receiving a 70 pin 40, passing through apertured knuckles 41, formed upon the opposite sides of the receptacle 10. The cover 34 is therefore pivoted to the receptacle 10 to swing in a vertical plane with relation thereto and 75 serves to close the upper end thereof for excluding foreign matter and has means to operate the valves to be next described.

The opening 14 in the pocket or passage 80 13, hereinabove described, is covered and uncovered by a vertically movable valve 42, the upper end of which is tapered, as shown at 43. When the valve 42 is in the lowermost position, as shown in Fig. 2^a, the opening 14 is uncovered, but when this valve 85 is moved upwardly, it covers the opening 14. The valve 42 is vertically moved by means of a rod 44 connected therewith, and having pivotal connection, as shown at 45, with the cover 34. The valve 42 is moved to the upper or closed position for covering the opening 14, when the cover 34 is raised.

Arranged within the inlet conduit 18 is a downwardly seating valve 46, preferably 90 formed of rubber, adapted when in the lowermost position to cover the discharge end of the bore 22, as clearly shown in Fig. 2. This valve also contacts with the spherically curved seat 47, and is thereby directed or guided to the discharge end of the bore 22, 100 as is obvious. The valve 46 has connection with a rod 48, extending upwardly through the opening 33 and having pivotal connection with the rear end of the lid 34, as shown at 49. It is obvious that when the cover 34 105 is in the closed position the valve 46 is seated and when the cover is elevated the valve is raised and water will discharge through the bore 22.

The operation of the apparatus is as follows:

When the animal, such as a cow or horse, desires to drink, she engages the up-turned lip 35 with the mouth and elevates the cover 34, thus gaining access to the interior of the drinking receptacle 10. This upward movement of the cover 34 elevates the valve 42 for covering the opening 14, and simultaneously raises the valve 46, uncovering the discharge end of the bore 22, whereby the water will pass from the discharge end of the inlet conduit 18, beneath the cap or plate 28, and discharge into the rear end of the receptacle 10, such water passing exteriorly 115 about the inlet conduit 18, in proximity thereto.

It is to be understood that the form of my invention herewith shown and described

is to be taken as a preferred example of the same, and that various changes in the shape, size, and arrangement of parts may be resorted to without departing from the spirit 5 of the invention or the scope of the subjoined claims.

Having thus described my invention, I claim:—

1. In apparatus of the character described, 10 the combination with a drinking receptacle, of an upstanding inlet conduit arranged within the drinking receptacle and attached to its bottom, a coupling carried by said bottom and leading into the inlet conduit and 15 having one end thereof extending to the exterior of said bottom for connection with a water supply pipe, a valve arranged within the inlet conduit to control the passage of the water therethrough, a valve for controlling 20 the discharge of water from the drinking receptacle, a movable cover to normally close the upper end of the drinking receptacle, and means connecting the valves with the cover.

25 2. In apparatus of the character described, the combination with a drinking receptacle, of an upstanding inlet conduit arranged within the drinking receptacle and having its lower end screw-threaded, a coupling 30 carried by the bottom of the drinking receptacle and having one end thereof extending above the bottom and screw-threaded for engagement with the lower end of the upstanding inlet conduit and its opposite end 35 extending below and exteriorly of the bottom and screw-threaded for engagement with a water supply pipe, means whereby the inlet conduit may be turned upon its longitudinal axis, a valve arranged within 40 the inlet conduit to control the passage of water therefrom, a valve for controlling the discharge of water from the drinking receptacle, and a movable cover to normally close the drinking receptacle and having connections with the valves.

45 3. In apparatus of the character described; the combination with a drinking receptacle; of a coupling formed upon the bottom of the drinking receptacle and extending above and 50 below the bottom, said coupling having its upper end internally screw-threaded and its lower end screw-threaded for engagement with a water supply pipe; a substantially vertical inlet conduit arranged within the 55 drinking receptacle and having its lower end reduced and externally screw-threaded for engagement within the upper end of the coupling, said inlet conduit having a large upper bore provided with a tapered lower 60 end and a contracted bore discharging into the large bore at the tapered end thereof; an adjustable element adapted for movement across the contracted bore; a valve arranged within the large bore of the inlet conduit

and having a substantially smaller diameter 65 than the large bore, said valve having its lower end tapered for coaction with the lower tapered end of the large bore; a valve for controlling the discharge of water from the drinking receptacle; a movable cover 70 connected with the receptacle; and means connecting the cover and valves.

4. In apparatus of the character described, 75 the combination with a drinking receptacle; of a coupling formed upon the bottom of the drinking receptacle and provided near its upper end with internal screw-threads and having its lower end adapted for connection with a water supply conduit; a substantially vertical inlet conduit arranged within the 80 drinking receptacle and having its lower end exteriorly screw-threaded for engagement within the upper end of the conduit, said inlet conduit having an upper large bore provided with a spherically curved 85 lower end wall and a contracted lower bore leading into the upper large bore at the spherically curved end wall thereof, said inlet conduit having a transverse screw-threaded opening which leads into the lower contracted bore; a bolt having screw-threaded engagement within the transverse screw-threaded opening and adapted for movement across the lower contracted bore; a valve arranged within the upper large bore 90 of the inlet conduit and having its lower end spherically curved to coact with the spherically curved end wall of the large bore; a valve for controlling the discharge of water 95 from the receptacle; a movable cover for the receptacle; and means connecting the cover and valves.

5. In apparatus of the character described; a drinking receptacle; an inlet conduit arranged therein in an approximately vertical position, said inlet conduit having an upper large bore provided with a spherically curved lower end wall, and a lower contracted bore leading into the large bore at the spherically curved end wall; a valve arranged 105 within the large bore and having its lower end spherically curved to coact with the spherically curved end wall; a cover pivoted to the drinking receptacle; and a link connected with the valve and pivoted 110 to the cover.

6. In apparatus of the character described, a drinking receptacle, a substantially vertical inlet conduit arranged therein and having its upper end open, a cap arranged upon 120 the upper end of the conduit and spaced therefrom and having a depending annular flange surrounding the upper end of the conduit and projecting downwardly beyond the upper end, a valve arranged within the 125 conduit, a movable cover for the receptacle, and means connecting the cover and valve.

7. In apparatus of the character described,

a drinking receptacle, a substantially vertical inlet conduit arranged therein and having its upper end open, a cap adapted to be arranged near and above the upper end of the conduit and carrying depending spacing flanges to contact with such upper end, an annular flange carried by the cap and depending therefrom to extend below the upper end of the inlet conduit and provided 10 with inwardly extending spacing lugs to contact with the side wall of the conduit, a valve operating with the conduit, and means to move the valve.

8. In apparatus of the character described, 15 the combination with a drinking receptacle, having a rear forwardly inclined bottom wall and a forward rearwardly inclined wall which joins the rear bottom wall, said rear bottom wall having a rearwardly inclined pocket formed therein and extending for substantially the entire length thereof; of a drain conduit connected with the bottom of the receptacle and adapted to receive water from the inclined pocket; a valve for 20 controlling the passage of the water from the pocket; an inlet conduit discharging into the receptacle; a valve for the inlet conduit; and a cover hinged to the receptacle and having connections with the valves.

30 9. In apparatus of the character described, the combination with a receptacle, of an overflow conduit arranged therein at one corner thereof, a perforated guard-plate disposed upon the top of the conduit and having legs adapted to be arranged inwardly and outwardly of the conduit, and means for supplying water into the conduit.

10. In apparatus of the character described; a drinking receptacle; an inlet conduit arranged within the receptacle with its 40 discharge end disposed a substantial distance above the bottom of the receptacle, said inlet conduit having means for connection with a water supply pipe located exteriorly of the receptacle; a valve arranged in the inlet conduit; an outlet valve for controlling the discharge of water from the

receptacle; a movable cover for the receptacle; and connecting means between the cover and said valves. 50

11. In apparatus of the character described, a drinking receptacle; an inlet conduit arranged within the receptacle with its discharge end disposed a substantial distance above the bottom of the receptacle and having its opposite end extending exteriorly of the receptacle for connection with a water supply pipe; a valve arranged within the inlet conduit; an outlet valve for controlling the discharge of water from the receptacle; a movable cover for the receptacle; and connecting means between the cover and said valves. 60

12. In apparatus of the character described, a drinking receptacle; an approximately vertically arranged inlet conduit disposed within the receptacle and provided with an upper enlarged bore having a tapered lower end and a contracted bore discharging into the large bore at the 70 tapered end thereof; a valve arranged to operate within the large bore of the conduit; means to supply water to the conduit; an outlet valve for the receptacle; a cover pivoted to the receptacle; and means connecting the cover and valves. 75

13. In apparatus of the character described, the combination with a drinking receptacle provided at one corner with an overflow conduit; a perforated strainer 80 plate held within said corner near the upper end of the overflow conduit; an inlet conduit discharging into the receptacle; a valve arranged within the inlet conduit; a cover pivoted to the receptacle; a discharge valve 85 for the receptacle; and means connecting the valves and cover.

In testimony whereof I affix my signature in presence of two witnesses.

JOHN MINOR BOTT'S LEWIS.
